CANINE MUZZLE

Anthony J. Lupo, Sr., 5321 NW. 180th Terrace,
Opa Locka, Fla. 33054

Filed Sept. 30, 1968, Ser. No. 13,764

Term of patent 14 years

Int. Cl. D30—04

U.S. Cl. D30—38

FIG. 1

FIG. 4

FIG. 2

FIG. 3

FIG. 1 is a perspective view of a canine muzzle showing my new design.

FIG. 2 is a side elevational view, with the obverse side being a mirror image thereof.

FIG. 3 is a bottom plan view.

FIG. 4 is a rear elevational view.

I claim:

The ornamental design for a canine muzzle, substantially as shown and described.
